UNITED STATES PATENT OFFICE.

FREDERIC C. ZEH, OF SAN FRANCISCO, CALIFORNIA.

WEATHERPROOF HINGE.

Application filed August 5, 1924. Serial No. 730,256.

To all whom it may concern:

Be it known that I, FREDERIC C. ZEH, a citizen of the United States, residing in the city and county of San Francisco, and State 5 of California, have invented a new and useful Improvement in a Weatherproof Hinge, of which the following is a specification.

My invention relates to improvements in hinges for hingedly mounting windows, 10 doors and the like within casements, and particularly to an improved hinge which will maintain a weather-proof connection between the window or door and the casement in all positions of the window or door.

15 The primary object of my invention is to provide an improved hinge adapted to form a weather-proof mounting for doors, windows, and the like.

Another object is to provide an improved 20 hinge which will form a strong and rigid mounting.

A further object is to provide an improved hinge which may be easily installed in connection with casements and sashes, and 25 which will also facilitate the removal of the sash from the casement.

I accomplish these and other objects by means of the device disclosed in the drawings forming a part of the present specification 30 wherein like characters of reference are used to designate similar parts through said specification and drawings and in which,

Fig. 1 is a vertical section through a window and casement showing the manner in which my improved hinge is used for mounting window sashes.

Fig. 2 is an enlarged sectional detail of my improved hinge.

40 Fig. 3 is a similar view showing the hinge with the window in the open position.

Fig. 4 is a broken front elevation of the hinge.

Referring to the drawings the numeral 1 45 is used to designate in general a sash 1 mounted within a casement designated in general by the numeral 2. The sash is hingedly supported within the casement by means of round bead 3 extending entirely 50 across the casement and having a groove 4 longitudinally disposed therein, said groove being adapted to receive one edge of a strip 6 secured in connection with the bead by means of screws 7 or other suitable securing means. The strip 6 is adapted

to be secured in connection with one edge of the casement by means of screws 8 applied through apertures 9 formed in the strip. A moulding 11 is secured between the strip 6 and the edge of the casement 2, said 60 moulding being provided with an arcuate surface slightly spaced from the adjacent surface of the bead 3 to form a recess 12, the purpose of which will hereinafter be more fully explained.

A bead engaging member designated in general by the numeral 13 is secured in connection with the edge of the sash 1 and adapted to pivotally engage the bead. 3. The member 13 is formed from sheet metal 70 shaped to form a socket portion 14 adapted to form a neat turning fit upon the head 3, said socket portion being open upon one side to accommodate the strip 6 and to permit a movement of the member 13 through 75 approximately 90° relative to said strip. The member 13 is secured to the sash 1 by means of an extension 16 formed by bending the sheet metal outwardly from the socket portion to form a lateral extension 80 substantially U-shaped in cross section and extending the entire length of the member 13, said extension being fitted into a groove 17 formed in the adjacent edge of the sash 1. A filler 18 is fitted between the wall portions of the extension to afford strength and 85 rigidity to the mounting. The extension is held in the groove 17 by means of screws 19 or other suitable securing elements applied through the sash 1 and engaging registering apertures 21 formed in the wall portions of the extension 16 and the filler fitted 90 therebetween.

In the drawings I have illustrated the hinge in connection with a window sash, 95 and in Fig. 1, I have illustrated a window construction wherein upper and lower sashes are mounted in a common casement. In operation, the strip 6 is first secured in connection with the bead, the member 13 moved 100 longitudinally onto the bead, and the strip 6 secured upon the edge of the casement 2 or upon a cross member 23, the moulding 11 being secured between the strip 6 and the casement by the same screws used for 105 securing the strip. The extension 16 of the member 13 is then secured to the sash by inserting said extension into the groove 17 and applying the screws 19. The open side of the socket portion 14 is so disposed that 110

when the window sash is in the closed position as shown in Fig. 2, and in the upper portion of Fig. 1 of the drawings, one edge of the member 13 will be received within the recess 12 between the moulding 11 and the bead 3, the opposite edge of the socket portion being spaced substantially ninety degrees away from the strip 6. When now the window is opened as shown in Fig. 3 and in the lower portion of Fig. 1, the first mentioned edge will be partially withdrawn from the recess and the opposite edge will be moved to abut against the strip 6 to prevent further movement. The moulding 11 is made to extend slightly above the center of the bead 3 so that when the window is fully opened the edge of the moulding will overlap the adjacent edge of the member 13.

The socket portion of the member 13 is made to fit neatly onto the bead 3 and by causing the edge of the socket portion to extend into the recess 12 and at all times the hinge effectively closes the space between the sash and the casement and in this manner forms a weather-proof mounting. The hinge is particularly useful in connection with windows which are arranged to open inwardly from the top, my improved device effectively excluding air, dust and moisture at the bottom of the window and preventing rain or water falling upon the window from draining past the hinge and into the room. However, my invention is not restricted to this particular application of the device as it is equally useful in connection with doors and in other connections wherein it is desired to maintain a weather-proof mounting. In connection with the use of my improved hinge for mounting windows as above described, it will be noted that the hinge permits the window to be swung inwardly to substantially horizontal position whereby the outer surface of the window may be conveniently washed, any excess water used being drained off outwardly and prevented from seeping past the hinge and into the room.

The hinge may be readily taken apart to permit the removal of the entire window from the casement by removing either the screws 8 or the screws 19. By removing the screws 8 the window and hinge may be removed together from the casement, while removal of the screws 19 will permit the window sash to be removed without disturbing the hinge itself.

Having thus described my invention what I claim as new and desire to secure by Letters Patent is,

1. A weather-proof hinge comprising a round bead mounted along one edge of a casement; and a bead engaging member mounted upon the corresponding edge of a sash mounted within the casement, said member having a longitudinally disposed socket

engaging the bead along the entire length thereof and forming a pivotal connection therewith.

2. A weather-proof hinge comprising a round bead mounted along one edge of a casement; a bead engaging member mounted upon the corresponding edge of a sash mounted within the casement, said member having a longitudinally disposed socket engaging the bead along the entire length thereof and forming a pivotal connection therewith; and a moulding mounted in association with the bead and having an arcuate surface spaced from one side of the bead to form a recess adapted to receive the adjacent edge of the bead engaging member.

3. A weather-proof hinge comprising a round bead mounted along one edge of a casement; a bead engaging member mounted upon the corresponding edge of a sash mounted within the casement, said member being formed from sheet metal shaped to form a socket adapted to pivotally engage the bead along the entire length thereof and provided with an extension detachably secured within a corresponding groove formed in a sash; and a moulding mounted in association with the bead and having an arcuate surface spaced from one side of the bead to form a recess adapted to receive the adjacent edge of the bead engaging member.

4. A weather-proof hinge comprising a round bead mounted along one edge of a casement; a bead engaging member mounted upon the corresponding edge of a sash mounted within the casement, said member being formed from sheet metal shaped to form a socket adapted to pivotally engage the bead along the entire length thereof and provided with a lateral extension formed by bending the metal outwardly and then back to form spaced walls adapted to be engaged within a groove formed in the edge of the sash; a filler mounted within a space between the walls; and securing means extending through the extension and the filler for rigidly securing the bead engaging member upon the sash.

5. A weather-proof hinge comprising a round bead mounted along one edge of a casement; a bead engaging member mounted upon the corresponding edge of a sash mounted within the casement, said member being formed from sheet metal shaped to form a socket adapted to pivotally engage the bead along the entire length thereof and provided with a lateral extension formed by bending the metal outwardly and then back to form spaced walls adapted to be engaged within a groove formed in the edge of the sash; a filler mounted within the space between the walls; and securing means extending through the extension and the filler for rigidly securing the bead en-

- gaging member upon the sash; and a moulding mounted adjacent the outer side of the bead and having an arcuate surface spaced from said bead to form a recess adapted to receive the adjacent edge of the socket and to overlap said edge at all times whereby a weather-proof connection may be maintained.
6. A weather-proof hinge comprising a round bead; means for detachably securing said bead along one edge of a casement; a bead engaging member having a socket adapted to pivotally engage the bead along the entire length thereof; and means for detachably securing the bead engaging member along the corresponding edge of a sash mounted within the casement whereby said sash may be hingedly connected to said casement.
- 20 7. A weather-proof hinge comprising a round bead having a longitudinally disposed groove formed in one side thereof; a strip secured within the groove and extending outwardly therefrom along the entire length of the bead; means for securing the strip upon one edge of a casement to hold the bead in parallel relation to said edge; a bead engaging member having a socket adapted to pivotally engage the bead along the entire length thereof; and means for rigidly securing the bead engaging member upon the edge of a sash mounted within the casement whereby said sash may be hingedly connected to said casement.
- 35 8. A weather-proof hinge comprising a round bead having a longitudinally disposed groove formed in one side thereof; a strip secured within the groove and extending outwardly therefrom along the entire length of the bead; means for securing the strip upon one edge of a casement to hold the bead in parallel relation to said edge; a bead engaging member having a socket adapted to pivotally engage the bead along the entire length thereof; and means for rigidly securing the bead engaging member upon the edge of a sash mounted within the casement whereby said sash may be hingedly connected to said casement; and a moulding secured between the strip and the casement, said moulding having an arcuate surface spaced from the adjacent surface of the bead to form a recess adapted to receive the adjacent edge of the bead engaging member.
- 40 9. A weather-proof hinge comprising a round bead having a longitudinally disposed groove formed in one side thereof; a strip secured within the groove and extending outwardly therefrom along the entire length of the bead; means for securing the outwardly extending edge of the strip upon one edge of a casement to hold the bead in parallel relation to said edge; and a bead engaging member adapted to pivotally engage the bead along the entire length thereof, said member being shaped from sheet metal to form a socket open upon one side to permit movement relative to the strip and having an extension formed upon the opposite side to be received within a groove formed in the edge of a sash mounted within the casement whereby the member may be rigidly secured upon the sash to hingedly connect the sash within the casement.
- 45 10. A weather-proof hinge comprising a round bead having a longitudinally disposed groove formed in one side thereof; a strip secured within the groove and extending outwardly therefrom along the entire length of the bead; means for securing the outwardly extending edge of the strip upon one edge of a casement to hold the bead in parallel relation to said edge; and a bead engaging member adapted to pivotally engage the bead along the entire length thereof, said member being shaped from sheet metal to form a socket open upon one side to permit movement relative to the strip and having an extension formed upon the opposite side to be received within a groove formed in the edge of a sash mounted within the casement whereby the member may be rigidly secured upon the sash to hingedly connect the sash within the casement.
- 50 11. A weather-proof hinge comprising a round bead having a longitudinally disposed groove formed in one side thereof; a strip secured within the groove and extending outwardly therefrom along the entire length of the bead; means for securing the outwardly extending edge of the strip upon one edge of a casement to hold the bead in parallel relation to said edge; and a bead engaging member adapted to pivotally engage the bead along the entire length thereof, said member being shaped from sheet metal to form a socket open upon one side to permit movement relative to the strip and having an extension formed upon the opposite side to be received within a groove formed in the edge of a sash mounted within the casement whereby the member may be rigidly secured upon the sash to hingedly connect the sash within the casement; and a moulding secured between the bead mounting strip and the casement, said moulding having an arcuate surface spaced from the adjacent surface of the bead to form a recess adapted to receive the adjacent edge of the bead engaging member whereby a weather-proof connection may be maintained.

In witness whereof I, hereunto set my signature.

FREDERIC C. ZEH.
